United States Patent Office.

ALBERT F. ALLEN, OF PROVIDENCE, RHODE ISLAND.

Letters Patent No. 96,863, dated November 16, 1869.

IMPROVED HOSE-LADDER STRAP.

The Schedule referred to in these Letters Patent and making part of the same.

To all whom it may concern:

Be it known that I, ALBERT F. ALLEN, of the city and county of Providence, and State of Rhode Island, have invented a certain new and useful Hose and Ladder-Strap.

My invention consists in the novel arrangement and combination of a strap, slide-ring, hooks, and handle, the whole constituting a novel and desirable article for the use of firemen in active service; and I do hereby declare that the following specification, taken in connection with the drawings furnished, and forming a part of the same, is a true, clear, and exact description thereof, reference being had to the drawings.

Figure 1 represents one of my hose and ladder-straps, in perspective.

Figure 2 represents the same, attached to hose, and suspended from the round of a fireman's ladder.

A is a leather strap, of any desirable length, and of the requisite strength.

B is a sliding band or ring, loosely fitted to the strap.

C is a hose-hook, secured to one end of the strap, and is arranged to engage with the sliding ring B and form a slip-loop.

D is a ladder-hook, attached to the other end of the strap, and is arranged to engage with the round of a ladder when desired.

E is a handle, secured to the end of the strap adjacent to the hook D.

The object of my invention is to meet a long-existing demand for a strap easily attached to, and detach-

able from hose during service at fires, and which can be readily secured to a ladder, and entirely obviate the necessity of grasping the hose with the hands.

My hose and ladder-strap possesses an obvious value in conveying charged hose up a ladder during active service, as it can be lifted from round to round, and left suspended therefrom while the fireman ascends unencumbered.

In practice, I find it desirable to have the strap of sufficient length to admit of twice encircling the hose with which it is to be used, as it can then serve as a holding-strap for the hose-pipe while in service, or the same strap, with a single wrap, may be used in handling the suction-hose, which is usually of a greater diameter.

By having the strap of a proper length, and provided with a suitable take-up arrangement, it will serve a useful purpose as a fireman's belt, the strap-hook engaging with the handle as a means of fastening.

Having thus described my invention, I claim as new, and desire to secure by Letters Patent—

As a new article of manufacture, the hose and ladder-strap, herein described, consisting of the strap A, provided with hooks, sliding band, and handle, for the purposes specified.

ALBERT F. ALLEN.
